UNITED STATES PATENT OFFICE

1,924,114

METHOD OF MAKING BRAKE SHOES

Edwin R. Evans, Chicago, Ill.

Original application March 20, 1931, Serial No. 524,011. Divided and this application March 18, 1932. Serial No. 599,625

4 Claims. (Cl. 29—152.1)

This invention relates to a new and improved method of making a brake shoe, and more particularly to a method of forming a brake shoe from a continuous rolled section.

5 Brake shoes have heretofore been made in a variety of ways, including castings and light metal stampings. In my prior application Serial No. 265,884, filed March 30, 1928, I have shown a shoe formed from a rolled section, and in my 10 application Serial No. 524,011, filed March 20, 1931, I have shown an improved rolled section shoe. The present application is a division of the application last mentioned and relates to the method of making the shoe covered in that 15 application.

It is an object to provide a method of making an improved brake shoe formed from a rolled section of standard shape and provided with an integral actuating portion.

20 It is an additional object to provide a method of making a shoe of this character in which the actuating face is integrally connected to and fully supported by a web of the rolled section.

25 It is a further object to provide a method of making a shoe having an integral hardened actuating wear face.

Other and further objects will appear as the 30 description proceeds.

I have shown certain preferred embodiments 35 of my invention in the accompanying drawings, in which—

Figure 1 is an elevation of my improved shoe applied to a brake assembly, the brake drum being cut away to show the interior parts;

35 Figure 2 is a similar view of a single brake shoe on an enlarged scale;

Figure 3 is a view of Figure 2 as seen from above;

40 Figure 4 is a view of Figure 2 as seen from below;

Figure 5 is a view of Figure 2 as seen from the left;

Figure 6 is a section of Figure 2 on line 6—6;

45 Figure 7 is a section of Figure 2 on line 7—7;

Figure 8 is a section similar to Figure 6 showing a modified form of construction;

Figure 9 is a view similar to Figure 8 showing a further modified form;

50 Figure 10 is a perspective view, partly broken away, showing the partially trimmed blank;

Figure 11 is a view similar to Figure 10 showing the blank after the web has been trimmed;

55 Figure 12 is a perspective view of the pivot end of the shoe after the forming operation; and

Figure 13 is a view similar to Figure 12 but showing the cam end of the shoe.

In Figure 1 the backing plate 11 is shown provided with bolts 12 by which it may be secured to a steering knuckle (not shown). The backing plate 11 carries a housing 13 which supports an adjustable brake shoe pivot pin 14. The bearing ends 15 of the shoes 16 pass through slots in the housing 13 to engage in grooves in the pin 14. The shoes 16 are T-shaped in cross section, being 65 provided with the cylindrical flange 17 and the inwardly extending web 18. The flange 17 carries the brake lining 19 adapted to engage the brake drum 20. The springs 21 are connected at one end to the shoes 16 and at the other end to the 70 backing plate 11 so that they serve to retract the shoes from engagement with the brake drum 20. The springs may impart angular thrusts to the shoes tending to urge them toward the backing plate, and the webs of the shoes may have raised 75 portions 40, 40 for engaging the backing plate. The portions 40 therefore require machining of only small surfaces.

The lower ends of the shoes, as shown, are 80 provided with bent up ends 22 which serve as actuating faces to engage the operating cam 23 carried by brake operating shaft 24. Both the web 16 and flange 17 are bent or forged so that the flange throughout its extent, including the bent up portion, is integrally and permanently 85 connected with the web.

In one method of manufacture, as shown in Figures 10 to 13, the shoes are formed from straight T-bars. These bars are first sawed to give pieces of the proper length for the desired 90 shoes. Then the webs have outer portions adjacent the ends of the blanks cut away on lines as shown in Figures 10 and 11 so as to eliminate excess metal. The ends of the blanks are then bent up, the metal of the web being forged or swaged 95 to bring it to the form shown in the drawings. There are no edges to be joined by the forging or swaging and there is no welding. The metal of the web is caused to flow to form the continuous web shown.

In the form shown the web 16 is of a depth similar to the depth of the wear face 22 so that this face is supported by the web throughout its height. The flange portion of the blank which forms the actuating face 22 is also deformed during the forming operation, being curved in cross section as clearly shown at 23 of Figure 4. Also where the shoe is to be used in a structure in which the shoe is in a plane at an angle to the 100 plane of the swiveling axis, the curved portion of 105

the bearing face may be formed on an angle as best shown in Figure 5. Due to this curved formation the edges of the flanges extend inwardly as shown at 24 and 25 of Figure 5.

5 The upper or pivot end 15 of the shoe may be formed by the same type of operations as the actuating end. The pivot end 15 has an end face 26 cut on an angle as shown in Figure 3 so as to fit in the angular grooves in the pivot pin 14 whereby axial movement of the pin will adjust the shoes.

A portion of the web 16 is shown bent over to give a bearing face 27 for a centralizer 28. This centralizer is shown in Figure 1 as a conical headed stud threaded into the backing plate 11.

10 The shoes may be suitably heat treated as desired, after the forming operations are complete. The pivot ends 15 and wear faces 23 may be hardened to resist wear, by the cyanide process

20 for example.

While the shoes have been described so far as being formed of T-shaped rolled section, it may be found desirable in large sizes and with wide shoes to use sections having a plurality of inwardly extending webs.

25 Figure 8 shows a section having a flange 30 and a pair of spaced webs 31 and 32. Figure 9 shows a channel section with a base 33 and legs 34 and 35. Sections such as

30 these with a plurality of webs permit strengthening the flange at a plurality of points and also permit equivalent rigidity with webs of less depth than would be necessary with a lesser number of webs.

35 The webs of less depth permit greater clearances in the assembly and also facilitate the forming operations of the ends of the shoes.

The forms of construction shown are to be taken as illustrative only, as the improved brake shoe is capable of variations and change to meet

40 differing requirements and I contemplate such changes and modifications as come within the spirit and scope of the appended claims.

I claim:

1. The method of making a brake shoe which comprises cutting a rolled section to the required length, said section having a flat face and a rearwardly extending reinforcing web, trimming excess metal from the end portions of the web, bending the section to arcuate form, and bending inwardly a portion of the flange and web to form an approximately radial cam face.

81 2. The method of making a brake shoe which comprises cutting a rolled section to the required length, said section having a flat face and a rearwardly extending reinforcing web, trimming excess metal from the end portions of the web, bending the section to arcuate form, and bending inwardly a portion of the flange and web to form an approximately radial cam face, the excess metal removed from the web being such as to permit the remaining metal to flow under forming pressure to form a continuous web integrally connected to the inwardly bent portion of the flange and a substantially uniform height and thickness.

90 3. The method of making a brake shoe which comprises cutting a rolled section to the required length, said section having a flat face and a rearwardly extending reinforcing web, trimming excess metal from the end portions of the web, bending the section to arcuate form, bending inwardly a portion of the flange and web to form an approximately radial cam face, and hardening the cam face.

100 4. The method of making a brake shoe which comprises cutting a rolled section to the required length, said section having a flat face and a rearwardly extending reinforcing web, trimming excess metal from the end portions of the web, bending the section to arcuate form, bending inwardly a portion of the flange and web to form an approximately radial cam face, and forming a reduced pivot on the opposite end of the shoe.

EDWIN R. EVANS.
